UNITED STATES PATENT OFFICE

159,957

HACK SAW

Richard D. Clemson, Middletown, N. Y.

Application January 22, 1949, Serial No. 408

Term of patent 14 years

(Cl. D93—4)

To all whom it may concern:

Be it known that I, Richard D. Clemson, a citizen of the United States and a resident of the city of Middletown, in the county of Orange and the State of New York, have invented a new, original, and ornamental Design for a Hack Saw, of which the following is the specification, reference being had to the accompanying drawing forming a part thereof.

Figure 1 is a side elevation of a hack saw showing my new design;

Figure 2 is a bottom view; and

Figure 3 is a top view.

The essential features of my design reside in those portions shown in full lines.

I claim:

The ornamental design for a hack saw, substantially as shown and described.

RICHARD D. CLEMSON.
